(57) **CLAIM**

The ornamental design for a curved firearm grip, as shown and described.

DESCRIPTION

FIG. 1 is a top front perspective view of a curved firearm grip, showing my new design;

FIG. 2 is a front elevational view thereof;

FIG. 3 is a rear elevational view thereof;

FIG. 4 is a right elevational view thereof;

FIG. 5 is a left elevational view thereof;

FIG. 6 is a top plan view thereof; and,

FIG. 7 is a bottom plan view thereof.

The evenly broken line in the drawings discloses the unclaimed portions of the curved firearm grip and the decorative pattern thereof; the dash-dot type broken line in the drawings discloses the unclaimed boundaries of the claims; the broken lines form no part of the claimed design.
